PYROPHORIC LIGHTING MECHANISM

Louis V. Aronson, Newark, N. J., assignor to Art Metal Works, Inc., a corporation of New Jersey

Application August 24, 1935, Serial No. 37,645

4 Claims. (Cl. 67—4.1)

My invention relates to pyrophoric lighters of the type comprising a torch utilizable for actuating the lighter mechanism to thereby produce a shower of sparks which ignite the charge of fuel held in suspension by the torch wick.

My invention has further reference to improvements in the general class of pyrophoric lighters noted above, such improvements contributing to the ease and efficient operation of the automatic mechanism forming an important part of the pyrophoric lighter.

Various other objects, advantages and features of my invention will become apparent from the following description.

15 My invention resides in the pyrophoric lighting mechanism, features and combinations of the character hereinafter described and claimed.

For an understanding of my invention and for an illustration thereof, reference is had to the 20 accompanying drawing, in which:

Figure 1 is a vertical, sectional view, partly in elevation, of my novel pyrophoric lighting mechanism;

Fig. 2 is a plan view of the arrangement shown 25 in Fig. 1;

Fig. 3 is a transverse, horizontal sectional view, partly in inverted plan, and is taken on the line 3—3 of Fig. 1 looking in the direction of the arrows;

30 Fig. 4 is a transverse, vertical sectional view, partly in elevation, of my novel mechanism;

Figs. 5 and 6 are sectional views, partly in elevation, showing novel torches as constructed in accordance with the invention; and

35 Fig. 7 is a fragmentary, detailed view illustrating a modification of a part of my novel mechanism.

As shown on the drawing, the device of my invention comprises a base 1 adapted to rest upon 40 any suitable supporting surface, said base preferably having a sheet of felt 2 adhesively or otherwise suitably secured to the lower surface thereof. Secured to and upstanding from the base 1 are a pair of vertical standards 3 to which a top plate 4 is suitably secured, as by the screws

45 5. As illustrated, the mechanism of my invention is disposed interiorly of a casing 6 which, if desired, may have an upper surface engaged by the periphery of the plate 4 and a lower flanged surface 6a resting upon the base 1. The shape of this casing 6 is clearly shown in Figs. 1—4 inclusive. It shall be understood that such casing may be of other suitable configuration and otherwise arranged as may be desirable.

55 Suitably secured, as by the screws 7, to the

lower surface of the plate 4 is a secondary plate 8 which forms the direct support for the various actuating members hereinafter described.

As shown in Fig. 4, the plates 4 and 8 are apertured to provide a passage through which extends the threaded upper end of a vertical tubular member 9 having a flange 9a engaging the lower surface of the plate 4. Secured to said upper end of the member 9 is a nut 10 threaded against the upper surface of the top plate 4 and which serves, therefore, in conjunction with the flange 9a, to anchor the tubular member 9 in vertical position as shown.

As disclosed on the drawing, the tubular member 9 serves as a support for a fuel casing 11 which, as shown, is filled with a mass of cotton 12 or other absorbent material, fuel, such as high test gasoline, being introduced in suitable manner into said fuel casing, as by passage through the opening normally closed by the closure cap 12a. As stated, the tubular member 9 supports the fuel casing 11 and, to this end, said fuel casing 11 may comprise an upwardly extending tubular extension 11a to which the lower end of the tubular member 9 is threaded. Further, it is desirable that the fuel casing 11, in alignment with the extension 11a, be formed with a downwardly extending tubular extension 11b utilizable for anchoring in vertical position any suitable tubular structure 13 of felt, cotton or the like. The tubular structure 13 is adapted to receive or cooperate with the lower end of a torch T and, more particularly, said tubular structure 13, if desired, may be of the detailed character disclosed in U. S. Letters Patent No. 1,986,754.

As shown in Fig. 4, a pair of spaced frame members 14, 15 are disposed in parallel relation below the plates 4 and 8, the frame member 14, preferably, being formed integrally with the plate 8 and the frame member 15 being suitably anchored, as by soldering, in the position shown in Fig. 4.

The aforesaid frame members 14 and 15 support a horizontal pin or member 16 on which a sleeve 17 is disposed for free rotatable movement, this sleeve having a first projecting lever arm 18 secured thereto and said lever arm, in turn, having a lateral pin 18a projecting therefrom. As shown in Fig. 1, a second projecting lever arm 19 is formed integrally with the lever arm 18, the remote end of said lever arm 19 having a pin-and-slot connection with a reciprocatory actuating bar 20, the lower end of which is freely slid able in a lateral extension 15a of the aforesaid frame member 15, the upper section of said

35

40

45

50

55

actuating bar 20 being freely slideable in aligned openings formed in the plates 4, 8, the extreme upper end of said actuating bar 20 terminating in a lateral bifurcated section 20a formed with 5 a slot 20b, Fig. 2. In accordance with the invention, the actuating bar 20 should be biased in an upward direction and, to this end, there may be utilized a spring 21 which is confined between the frame member extension 15a and a shoulder formed on the actuating bar 20, Fig. 1.

Freely rotatable on the aforesaid sleeve 17 at one end thereof is a second sleeve 22 to which a disk 23 is secured for rotatable movement therewith.

15 Projecting laterally from a forward section of this disk is a pin 23a to which one end of a coiled spring 24 is secured, the other end of said spring being secured to the aforesaid pin 18a.

The aforesaid frame member 15 comprises a 20 rearward extension 15b which carries a lateral pin 25 to which, at the end of a spacing sleeve 26, a pawl 27 is pivoted, the pawl being biased in a counter-clockwise direction, Fig. 1, by a suitable spring 28. As illustrated in Figs. 1 and 3, this 25 pawl is adapted to be maintained by the spring 28 in clutching relation with a lateral section 23b of the aforesaid disk 23.

The pawl 27 comprises a section 27a, Fig. 1, adapted, as hereinafter described, to be engaged 30 by a nose 18b of the aforesaid lever arm 18 whereby said pawl 27 is rocked in clockwise direction, Fig. 1.

The aforesaid disk 23 is of such diameter that it extends thru aligned slots formed in the plates 35 4 and 8, said disk 23 terminating above the latter in a gear segment 23c disposed in meshing relation with a pinion 29 freely rotatable on a horizontal pin or member 30 mounted in fixed position in any suitable manner. Thus, for example, 40 one end of the pin 30 may be mounted in an integral section 31 of the aforesaid plate 8, said section 31 being formed as a standard which projects upwardly through a passage formed in the plate 4. The other end of the pin 30 may be 45 mounted in a section 15c of the frame member 15, said section 15c projecting upwardly through aligned slots formed in the plates 4 and 8.

In accordance with the form of the invention herein disclosed, the aforesaid pinion 29 is mounted 50 on and rotatable with the hub 32a of a ratchet wheel 32, this ratchet wheel 32 and its hub being freely rotatable and also freely movable longitudinally on the aforesaid pin 30. As shown in Fig. 4, a helical spring 33, disposed around the 55 pin 30, is utilized to bias the ratchet wheel 32 in a direction from left to right, Fig. 4.

Rotatably disposed on the pin 30 is a hub 34a of a second ratchet wheel 34, this hub 34a carrying, for rotative movement therewith, a wheel 60 35 having a serrated or roughened face coactable with a pyrophoric element 36 projecting in part from a tube 37 extending downwardly through the plates 4 and 8 and being anchored, preferably, to the aforesaid frame member 15. As shown in 65 Figs. 1 and 3, the lower end of the tube 37 has a cap nut 38 threaded thereinto, this nut maintaining under compression a helical spring, not shown, which is disposed within the tube 37 and which biases the pyrophoric element 36 into engagement with the serrated wheel 35.

70 The ratchet wheels 32 and 34 are provided with surfaces disposed transversely of the pin 30, these surfaces facing each other and being provided, respectively, with sets of ratchet teeth which co- 75 act with each other as indicated in Fig. 2. These

sets of ratchet teeth are so arranged that, during movement of the pinion 29 in a counter-clockwise direction, Fig. 1, said pinion idles with respect to the serrated wheel 35. However, during movement of the pinion 29 in a clockwise direction, Fig. 1, the sets of ratchet teeth are in clutching relation and, therefore the serrated wheel 35 is caused to move with the pinion 29 during clockwise movement of the latter.

As clearly appears from a consideration of Fig. 10 2, the lateral section 20a of the actuating bar 20 and particularly the slot 20b thereof is disposed in alignment with the lateral axis of the serrated wheel 35. Accordingly, when said lateral section 20a is depressed into its lowermost 15 position, as hereinafter described, it results that said lateral section 20a is in the direct path of sparks produced by action of the serrated wheel 35 on the pyrophoric element 36.

As illustrated, the sparking means described 20 above is covered by a casing 39 which is suitably secured to the plate 4, as by the screws 40. This casing, between said sparking means and the actuating bar 20, is open so as to permit free 25 passage of the pyrophoric sparks from right to left, Fig. 1.

A torch of any suitable character may be used 30 for actuating the herein described mechanism. At present, however, a torch T of the general character disclosed in Figs. 4 and 5 is preferred.

As shown, the torch T comprises a handle section 41 provided preferably with a knurled head 41a. Disposed interiorly of and projecting from one end of the handle section 41 is a sleeve 42 having a peripheral flange 42a engaged by an 35 interior shouldered surface of a cap member 43 which may be freely moved over the surface of the sleeve 42 and then threaded to the lower end of the handle section 41. Threaded to the interior surface of the sleeve 42 is a second sleeve 44 40 which, at its lower end, is attached to one end of a wick 45 of any suitable type, for example, as well known in the pyrophoric lighter art, this wick, as shown, being adapted to extend slightly beyond the lower surface of the sleeve 42, which 45 is provided with a shoulder 42b forming a neck of restricted diameter for the end of said wick. In accordance with the invention, the handle section 41 is utilized to move the sleeve 44 interiorly of and with respect to the sleeve 42. To 50 this end, any suitable arrangement may be utilized such, for example, as herein exemplified by the square or other polygonal rod 46 fixed to the handle section 41 and which extends, in freely slideable relation, interiorly of a passage of corresponding configuration formed interiorly of the sleeve 4.

As will readily be understood, the above noted cap member 43 prevents longitudinal movement of the sleeve 42 with respect to the handle section 60 41 while permitting free rotative movement of said sleeve and handle section with respect to each other. Accordingly, the exposed surface of the sleeve 42 may be held in the fingers of one hand while rotating the handle section 41, this 65 operation causing the sleeve 44 and the thereby-carried wick 45 to be so moved that the wick end is moved either into or out of the lower neck section of the sleeve 42. With such an arrangement, the length of the protruding wick section 70 may be adjusted with nicety and, as the wick burns away, new surfaces thereof may be exposed for use as desired. Obviously, such an arrangement is highly desirable because rendering the use of a long wick practical, in a torch of the 75

character described, such long wick having the advantageous function that it is capable of storing a relatively large quantity of fuel.

In the modified form of torch T! shown in Fig. 5, there is provided a handle section 48 having a serrated operating surface 48a. One end of a sleeve 49 is received in a passage formed in one end of said handle section, this sleeve being secured to the handle section for rotatable movement only by a sleeve nut 50, the latter engaging a shouldered surface 49a of the sleeve 49 as shown. Disposed interiorly of the sleeve 49 is a tubular wick 51 formed of suitable material as known to the art. Secured to the handle section 15 48 is a rod 52 of square or other polygonal configuration, this rod extending interiorly and longitudinally of the wick 51 in close-fitting relation and being of somewhat greater length than the sleeve 49. The latter, namely, the sleeve 49 is 20 provided, adjacent its lower end, with interior screw threads 49b, these threads being closely engaged by the wick 51.

The wick 51 normally projects beyond the lower end of the sleeve 49 to some extent as indicated. 25 When it becomes desirable to advance or retract said wick, the sleeve 49 is held by the fingers of one hand and the handle section 48 is turned in one direction or the other. The rod 52 turns with the handle section 48 and the wick 51 turns with 30 said rod 52. The rod 52 crowds the exterior surface of the wick 51 against the threads 49b and, since said wick turns with respect to the stationary threads 49b, it results that the wick is either retracted or advanced as desirable.

35 With a torch T!, the lower end of the rod 52 engages a cup-shaped member or other part carried by the actuating bar 20, or equivalent. With a torch T, the shoulder 42b, or equivalent, engages a surface defining a recess in the actuating bar. As will clearly appear, the wick end of the torch T to be ignited is disposed, ordinarily, below the lateral section 20a of the actuating bar whereas with the torch T!, the ignitable wick end ordinarily, is disposed above said lateral section, or equivalent.

45 In order to effect operation of the herein disclosed mechanism, the torch T is withdrawn from the tubular member 9. At this time, the exposed wick end will have taken up a charge of fuel from the fuel casing 11. Thereupon, the extreme lower end of the torch sleeve 42 is passed downwardly through the slot 20b of the actuating bar 20, such downward movement of the torch T continuing until the sleeve shoulder 42b engages the surface defining said slot 20b. Thereupon, the application of downward pressure to the torch T causes the actuating bar 20 to be moved downwardly from the position thereof shown in Fig. 1. In so doing, the lever arm arrangement 18, 19 is swung in a counter-clockwise direction, Fig. 1, with the result that the pin 18a recedes from the nose 23d of the disk 23 to thereby substantially increase the tension of the spring 24. As stated, this spring 24 is connected to the lever arm arrangement 18, 19 and also to the disk 23 but increase in tension of the spring 24 as just described does not cause movement of the said disk 23 because, during the movement of said lever arm arrangement described above, the disk 23 is locked by the pawl 27 in the position shown in Fig. 1.

70 During continued movement of the lever arm arrangement 18, 19 from the position shown in Fig. 1, the nose 18b of the lever arm 18 approaches and eventually engages the section 27a of the pawl 27. Thereupon, by application of pressure

to said pawl 27 by the lever arm nose 18b, the pawl 27 is swung clockwise from the position shown in Fig. 1 to thereby release the disk 23 at its lateral section 23b so that the latter moves counter-clockwise, Fig. 1, with a snap action 5 under the influence of the energy just stored in the spring 24 as described above. This counter-clockwise movement of the disk 23 continues until the nose 23d thereof again comes into engagement with the pin 18a. 10

When the above described counter-clockwise movement of the disk 23 occurs, the lower end of the torch T has moved to such a position that it is only slightly above the upper plate 4 of the herein described mechanism, said lower end of 15 the torch T, at this time, being in the direct path of sparks produced by action of the serrated wheel 35 on the pyrophoric element 36.

The sparks just referred to are produced by the herein described snapping movement of the disk 20 23 in a counter-clockwise direction, Fig. 1. Said disk 23, when moving in the direction last noted, causes the pinion 29 to partake of a step of clockwise movement, Fig. 1. When the pinion 29 thus moves, the ratchet faces of the members 32 and 34 are in clutching relation and, therefore, the serrated wheel 35 partakes of a step of movement in a clockwise direction, Fig. 1, corresponding with the step of movement imparted to the pinion 29. As a result, a shower of pyrophoric sparks 30 are produced, these sparks passing along a path tangentially of the serrated wheel 35 to thereby ignite the charge of fuel at the lower end of the wick 45.

35 In this manner the torch T is caused to have a freely burning flame which may be utilized for any desired purpose. Thus, the flaming torch may be utilized for the ignition of cigars, cigarettes, pipes, gas burners, etc., etc., and, in so doing, the torch may be passed from hand to hand as desired. When the torch T has served its intended purpose, it may be re-inserted in the tubular member 9; either before or after the flame at the lower wick end has been extinguished although, preferably, such flame is extinguished prior to re-insertion of the torch T in the tubular member 9. 40

45 As soon as the torch T is removed from the lateral end 20a of the actuating bar 20, the various parts automatically return to their respective normal positions as shown on the drawing. Thus, the spring 21, which previously had been compressed in response to downward movement of the actuating bar 20, is released for expansion. When thus expanding, the spring 21 elevates the 50 bar 20 to its normal position as shown in Fig. 1, the lever arm arrangement 18, 19 and the disk 23 moving substantially as a unit in a clockwise direction, Fig. 1, until these parts have returned to their respective positions shown in Fig. 1. While thus moving the pin 18a remains in engagement with the nose 23d of disk 23 and, eventually, at the conclusion of such return movement, the pawl 27 returns to latching position 55 with respect to the lateral section 23b of the disk 23. 60

65 When the disk 23 moves clockwise to its normal position as shown in Fig. 1, counterclockwise movement Fig. 1, is imparted to the pinion 29. 70 During such counterclockwise movement of said pinion 29, the ratchet face associated therewith idles with respect to the adjacent ratchet face, this action occurring in a ready manner inasmuch as the pinion 29 is freely movable longi- 75

tudinally of the pin 30 against the biasing action of the spring 33.

In the manner noted above, the various parts are returned to their respective normal positions as shown on the drawing and, when thus normally positioned, the device is in condition for subsequent operation which occurs in the manner hereinbefore described in detail when the actuating bar 20 is again depressed by the application 10 of pressure thereto by the torch T.

An important feature of the present invention relates to the arrangement wherein the lower necked end of the torch T is adapted to be passed into and through a recess such as the recess 20b 15 shown in Fig. 2, the shoulder 42b coming into engagement with the surface defining said recess. With an arrangement of this character, the lower wick end is disposed in the path of the pyrophoric sparks in a very advantageous manner.

20 In Fig. 2, the opening in the lateral section 20a forming the bifurcation is smaller than the diameter of the sleeve neck section below the shoulder 42b. Therefore, said neck section may not be passed laterally through said opening. In Fig. 7, 25 a modified construction is shown wherein a lateral section 20d of the actuating bar is provided with a V-shaped notch adapted to have the shouldered end 42d of a torch sleeve passed laterally thereinto, the arrangement being such 30 that the torch sleeve, when thus positioned, has its associated wick in the direct path of sparks projected from the adjacent serrated wheel 35.

Another important feature of the present invention relates to the ratchet arrangement for 35 effecting unidirectional movement of the serrated wheel 35. This is accomplished without requiring the use of the customary pivoted pawl. The two ratchet surfaces disclosed herein cooperate in an advantageous manner to drive the serrated 40 wheel and, due to the fact that the ratchet member 32, 32a together with the thereby-carried pinion 29 are readily slideable on the member 30, it results that the necessary idling action is necessarily obtained. In short, the disclosed 45 ratchet mechanism is simple, efficient and reliable. It fulfills all requirements in a very satisfactory manner.

Supplementing the foregoing, it is to be noted 50 that the arrangement of the sparking means, actuating bar and torch receptacle (tubular member 9) is advantageous and desirable. The mechanical arrangement is of a simplified type, the configuration of the casing and the supporting arrangement therefor are desirable from the 55 purchaser's viewpoint and also from the manufacturing viewpoint, and, in addition, there are other detailed improvements as will be obvious to those skilled in the art.

While the invention has been described with 60 respect to certain particular preferred examples which give satisfactory results, it will be understood by those skilled in the art after understanding the invention, that various changes and modifications may be made without departing 65 from the spirit and scope of the invention and it is intended therefore in the appended claims to cover all such changes and modifications.

What is claimed as new and desired to be secured by Letters Patent is:

1. A lighter construction, comprising a receptacle, a rotatable sparking wheel, a pyrophoric member bearing against said wheel, a depressible actuating member extending upwardly from said receptacle adjacent said wheel, mechanism within said receptacle and operable upon depression of said actuating member to cause said wheel to rotate and thereby project sparks, a torch engageable with said actuating member to depress the latter, said torch having a wick for protruding from its lower extremity into the path of said sparks, said torch also having a rigid shoulder portion just above the protruding portion of the wick, the upper end of said actuating member having a transversely extending portion overhanging the path of said sparks and formed to embrace said shoulder portion with the lower tip of the wick depending into said path of the sparks as said actuating member is depressed by said torch. 10

2. A lighter construction, comprising pyrophoric sparking mechanism for projecting a stream of sparks, a depressible member for actuating said mechanism, said member having a portion overhanging the path of said sparks, and a torch engageable with said portion to depress said member, said torch having a wick downwardly protruding at its lower extremity and also 25 having a rigid shoulder just above such protruding wick portion, said overhanging portion being formed to embrace said shoulder, with the wick depending into said path of the sparks as said actuating member is depressed by said torch. 30

3. A lighter construction, comprising pyrophoric sparking mechanism for projecting a stream of sparks, a depressible member for actuating said mechanism, said member having a portion overhanging the path of said sparks, a 40 torch engageable with said portion to depress said member, said torch having a wick downwardly protruding at its lower extremity and also having a rigid shoulder just above such protruding wick portion, said overhanging portion being 45 formed to embrace said shoulder, with the wick depending into said path of the sparks as said actuating member is depressed by said torch, and means for adjustably securing the wick within said torch, with the wick protruding a predetermined desired distance below said shoulder. 50

4. In pyrophoric lighting mechanism, a casing, a detachable cover therefor, a pyrophoric sparking mechanism assembly mounted on said cover and partially within said casing, a tubular member extending down through and depending from said cover, a fuel container within said casing below said mechanism and supported solely by said tubular member and communicating therewith, and a torch adapted to be removably supported within said tubular member with the lower end of said torch received in said fuel container, said torch, when removed from said tubular member, serving as an operating means for said pyrophoric sparking mechanism, said mechanism, tubular member and fuel container being removable from the casing as an assembled unit carried by said cover. 60

LOUIS V. ARONSON.
